WRENCH FOR THREADLESS DRILL PIPE

Alexander Boynton, San Antonio, Tex.

Application September 22, 1938, Serial No. 231,212

6 Claims. (Cl. 81—90)

My invention relates to wrenches, primarily for drill pipe connection and, particularly, threadless and semi-threadless drill pipe connections, as illustrated and described in my co-pending application for patent, Serial No. 231,211, filed September 22, 1938. Some features of this wrench, however, are adapted to be embodied in the construction of all wrenches.

The objects are to provide (1) a wrench that has built-in means for administering the momentary shock necessary to make up the connection or to break it out without the application of great steady force, (2) a wrench that does not require the use of hammers, levers, or extensions on handles in order to develop the necessary force required to make up or break out pipe connections, (3) a wrench which may be quickly applied without having to engage completely around the pipe, (4) a wrench which may be employed in connection with the invention in my said co-pending application in a manner that will not mash, score, or otherwise damage the pipe, (5) a wrench that acts to hold itself in operating position without the employment of reciprocating means, and, (6) a wrench that is always free to be released and which never "sticks" or "freezes" to the pipe.

A U-shaped portion, with keys or projections adapted to engage the driven member, is engageable over the pipe by lateral movement and has attached to it another element, also adapted to be engaged upon the pipe by lateral movement, and further adapted to become secured about the coupling by a slight longitudinal movement, which movement and slight rotation engages together the driving and driven members and, at the same time, secures the wrench in operating position.

I attain the foregoing objects by mechanism illustrated in the accompanying drawings, in which—

Fig. 1 is a top view of the assembly shown in Fig. 2.

Fig. 2 is an isometric view of the wrench embodying this invention.

Fig. 3 is an outside view of one form of my threadless drill stem connection for which this wrench is adapted.

Fig. 4 is a longitudinal section on the line 4—4, Fig. 1.

Fig. 5 is an isometric view of the key 3 in Figs. 2, 4, and 6.

Fig. 6 is a bottom view of assembly shown in Fig. 2.

Similar characters of reference refer to similar parts throughout the several views.

The upper shell member 1 may be threadedly connected to lower shell member 2, the upper end 5 of which locks against the flange 1c, as appears in Figs. 2 and 4. The upper member 1 has a U-shaped upper end 1d with lateral opening 1f wide enough to receive the drill pipe 6, Fig. 3, with slight clearance. The lower member 2 also 10 has a lateral opening 2a, likewise wide enough to receive the drill pipe with slight clearance, the openings or distances 1f and 2a being equal, but the lower member in its circumference describes somewhat more than a semi-circle, and has an 15 inside diameter slightly greater than the outside diameter of the coupling 7, Fig. 3, in order to provide that the member 2 will have a free slid-able fit over the coupling.

The member 1, Figs. 2 and 4, has dovetailed 20 openings in its lower end, adapted to closely receive the keys 3, having lower extensions 3a, adapted to be engaged within the slots 8b of the head 8a of spiral key member 8, the inner slope of the extensions 3a being at the same angle as the slots 8b and the upper end of head 8a. The dovetailed upper portion of the keys 3 taper in-wardly so that the keys may be placed from the outside into conforming slots in the lower end 25 of member 1, where these keys will be secured by and within the threaded upper end of member 2, as clearly appears in Fig. 4, also appearing in Figs. 1 and 6.

The handles 5 are connected by a semi-circular band 5a, having an opening within its inner side 35 to slidably receive the dovetailed rib 1a, which rib is integral with the member 1. After the semi-circular band 5a has been engaged over the semi-circular rib 1a, as in Fig. 2, the bumpers 4 are slidably engaged over each end of the rib 1a 40 and secured there by welds 4a, Figs. 2 and 6.

To place the wrench in operating position upon the drill pipe connection, such as illustrated in Fig. 3, the assembly, as shown in Fig. 2, is placed relative to Fig. 3 in the position occupied by the section in Fig. 4, i. e., the assembly is moved lat-erally over the drill pipe 6, which is admitted through the side openings 1f and 2a, the lower end member 2, having its bottom end internally beveled at 2b to facilitate engaging over the coupling, being then somewhat above the cou-pling 7 and the head 8a. The assembly is then moved downward, the lower shell member en-gaging over the coupling 7 until the internally beveled lower end 1g of the upper shell member 55 rests upon the similarly beveled upper end of

head 8a. If, in this movement, the lower end 3a of the keys should engage the head 8a between the slots 8b, slight rotation of the wrench assembly, of course, will cause the key extensions 3a to find and engage within the slots 8b in which the key lower extensions are adapted to engage, the lower beveled surface of the key extensions being at the same angle as the inclined slots 8b.

The wrench assembly being engaged over the drill pipe 6 and coupling 7, as described in the preceding paragraph, the spiral key member 8, having its spirals engaging between the spiral lands 6a of the drill pipe and opposite lands in the coupling, may be rotated in one direction to remove it or in the opposite direction to replace it.

The play between the handles 5 and bumpers 4 enables the connection to be made up tightly, or easily broken out, by a quick rotary jar in one direction or the other, as may be required. In breaking out ordinary rotary drill pipe, it is frequently necessary to hammer the couplings or tool joints and, in making up the joints, it is common practice to screw the threads together as tightly as possible with a wrench, and then to strike the wrench handle several times with a sledge hammer to make sure the joints are tight enough. It is then frequently necessary to strike the wrench handle on the opposite side to get the wrench loose. Much time is thereby wasted and accidents frequently happen. The built-in jarring or shocking means of the wrench herein disclosed is believed to save much time, promote safety, and increase efficiency, as compared to the now employed means for making and breaking drill pipe connections. The openings 5b are to receive a cable for the purpose of suspending the wrench balanced against a weight in order that the wrench may be quickly and easily applied for the purpose of making up or breaking out the drill stem, such balancing means being generally employed on drilling rigs for wrenches too heavy for convenient manual handling. The openings 5c are for attaching a rope or cable if more than manual force, in some cases, should be required.

Great speed is desired in making and breaking all drill pipe connections and to enable such speed to be attained the U-shaped upper end 1d between the flange 1b and connection band 5a is provided for a "cat line" to be wrapped around. In Figs. 1, 2, 3, and 6 the outermost position of the drill pipe is indicated by the line 1e. It will be observed that the cat line, in being wrapped about the U-shaped upper end, will clear the drill pipe for the obvious purpose of avoiding unnecessary friction between the rope and drill pipe.

It is obvious that mechanical changes may be made in the structure, and that equivalents may be substituted for the parts shown; and I reserve the right to make such mechanical changes, substitutions, and adaptions within the scope of the invention, as comprehended by the stated objects and appended claims.

I claim:

1. A wrench for connecting and disconnecting drill pipe sections which are coupled together with a locking bushing comprising a body, an open side therein to fit said body laterally about the pipe, a seat in said body to rest on said

bushing, keys projecting from said seat to be received by said bushing when said body is moved along the pipe against said bushing, and handles on said body to rotate the wrench and bushing.

2. A wrench for connecting and disconnecting drill pipe sections which are coupled together with a locking bushing comprising a body, an open side therein to fit said body laterally about the pipe, a seat in said body to rest on said bushing, keys projecting from said seat to be received by said bushing when said body is moved along the pipe against said bushing, handles on said body to rotate the wrench and bushing, and means loosely mounting said handles on said body so that a jar may be imparted to the body to start or complete the turning of the bushing.

3. A wrench of the character described including upper and lower body portions, keyways in the base of the upper portion, keys in said ways, threaded areas on said portions to lock said keys in said ways when threaded together, a handle on said wrench, and a jar connection for said handle including a dove tail guide ring on which the handle is slideable about said body.

4. A wrench of the character described including upper and lower body portions, keyways in the base of the upper portion, keys in said ways, threaded areas on said portions to lock said keys in said ways when threaded together, a handle on said wrench, and a seat on said wrench to receive a cat line to spin the wrench.

5. In a wrench of the character described to fit a pipe coupling having slots therein, an upper shell having a lateral longitudinal opening to admit a pipe, a lower shell threadedly connected therewith and having a lateral longitudinal opening adapted to register with said first opening, said second shell being adapted to fit axially over the pipe coupling, keys dovetailed into said upper shell and extending therebelow to engage the slots in the coupling, said keys being bevelled so as to be removably secured by said lower shell, a circular bevelled rib about the exterior of said upper shell, a handle member dovetailed with and slideable upon said rib, bumpers at either end of said rib to limit the movements of said handle member and to transmit the shock thereof to said keys and coupling, means to connect a cable for suspending said wrench in operative position, means for connecting a cat line to said handles, and means upon said upper shell to receive and support a cat line.

6. In a wrench of the character described to fit a pipe coupling having vertical slots therein, an upper shell having a lateral longitudinal opening to admit a pipe, a lower shell connected therewith and having a lateral longitudinal opening adapted to register with said first opening, said second shell being adapted to fit axially over the pipe coupling, keys in said upper shell and extending therebelow to engage the slots of the coupling, a ribbed exterior on said upper shell, a handle member slideable upon said rib, bumpers at either end of said rib to limit the movements of said handle member and to transmit the shock thereof to said keys and thence to the coupling, and means upon said upper shell to receive and support a cat line.

ALEXANDER BOYNTON.
